UNITED STATES PATENT OFFICE

LESLIE W. BLOCK, OF WEBSTER GROVES, MISSOURI

HOLDER FOR CASEMENT WINDOWS, DOORS, OR THE LIKE

Application filed November 17, 1928. Serial No. 320,119.

My invention relates to holders for doors, casement windows or the like and more particularly to holders which are so arranged as to automatically maintain the door or window in a predetermined open position.

Heretofore such holders which have been provided for doors could not be used on casement windows because these holders depended upon an engagement with the floor to maintain the door in desired position. The holders which were adapted for use with casement windows were unsightly and expensive both in cost of manufacture and in cost of installation.

The object of my invention is to provide a holder for doors or casement windows which is substantially hidden from view and which is simple and cheap both to manufacture and to install.

My invention is fully shown in the accompanying drawings wherein similar characters are used to designate similar parts: Fig. 1 shows one form of holder embodying my invention installed on a casement window; Figs. 2 and 3 show in section the holder in different positions; Figs. 4 and 5 show details of construction of the device of the first three figures; Figs. 6 and 7 show one modified form of the holder and Figs. 8 and 9 and 10, 11 and 12 show other modified forms of holders including embodiments of my invention.

In the embodiment of my invention shown in Figs. 1 to 5, inclusive, the holder is comprised in a hinge of the general type shown and described in United States Letters Patent No. 1,683,814 heretofore issued to me on September 11, 1928. The hinge has a leaf 1 carried by the window 2 and a leaf 3 carried by the jamb 4. A pin 5 extends through the knuckle 6 of the hinge and, preferably, has its lower end threaded in the knob 7, for the reasons more fully outlined below. The upper tubular portion of the knuckle 6 carried by the leaf 3 of the hinge has the notches 8 adapted to receive the lugs 9 which project downwardly from the head of the pin 5 or under certain conditions outlined more fully below to receive the base of the stop member 10 which extends outwardly from the pin 5

and then downwardly between the leaves 1 and 3 of the hinge. When the lugs 9 on the head of the pin 5 and the base of the stop member 10 are seated in the notches 8 the stop member 10 will be maintained in fixed relation to the leaf 3 of the hinge which leaf, as described above, carries the upper tubular portion of the knuckle 6 of the hinge. When the door or window upon which the hinge is used is opened the stop member will engage the other leaf 1 of the hinge, as shown in Fig. 2 to stop the opening movement of the hinge and, in turn, to stop the opening movement of the door or window. I prefer that the stop member 10 is disposed tangentially of the head of the pin 5, as shown in Figs. 3 and 5, so that the entire face of the stop member will engage the leaf as shown in Fig. 2.

The holder also includes automatic means for maintaining the hinge and, of course, the door or window in this open position and in this form of my invention the means consists of a spring lock arranged in a casing 11 fixed to the leaf 1. The bolt 12 of the lock is held in normal extended position by the spring 13 and has a shoulder 14 which bears against the inside of the end of the casing 11 to keep the bolt 12 from being extended too far by the spring 13. The outer face of the bolt 12 is beveled in the usual manner so that when the door or window is opened and as the leaf 1 is moved into engagement with the stop member 10 the stop member will first engage the beveled face of the bolt and as the opening movement is continued the bolt will be moved inwardly in the casing 11 against the action of the spring 13. When the leaf 1 comes into engagement with the stop member 10 the stop member will have moved past the bolt 12 and the spring 13 will move the bolt to hold the leaf 1 and stop member 10 in engagement and thereby lock the hinge in open position. When it is desired to close the door or window the bolt 12 may be withdrawn by manually moving the plunger 15.

In the form of my invention shown in Figs. 1 to 5, inclusive, the hinge may be used on doors or windows which open to the right as well as those which open to the left, as shown in the figures. When the hinge is so used

it is installed upside down and the knob 7 threaded on the lower end of the pin 5 will keep the pin 5 from falling out. It may be readily seen that in this form of my invention the degree to which the window is opened 5 may be adjusted by loosening the knob 7, moving the pin 5 longitudinally to carry the lugs 9 and the base of the stop member 10 out of the notches 8 and then turning the pin to decrease or increase the angle of the stop member 10 with the leaf 3. When the stop member is in desired position in respect to the leaf 3 the pin is moved longitudinally to bring the lugs 9 and the base of the stop member 10 into the notches 8 and the knob 7 is tightened.

In the embodiment of my invention shown in Figs. 6 and 7 the stop member 16 is fixed to the leaf 3 and therefore cannot be moved 20 in relation thereto to adjust the opening movement of the door or window to which it is applied. However, if it is desired to open the door or window to a degree less than the degree allowed by the stop member 16 the door 25 or window will be held by the spring 17 carried by the leaf 1 and which contacts with and follows the contour of a serrated drum 18 fixed to the leaf 3 above the stop member 16. Preferably, the spring is maintained in better 30 contact with the drum 18 by a roller 19 positioned as shown in Fig. 6.

Also, in this embodiment of my invention the bolt 12^a of the locking means has both 35 sides beveled so that a pressure upon the door or window either in opening or closing the window will move the stop member 16 to exert a pressure against the beveled face of the bolt to move the bolt inwardly.

In the embodiment shown in Figs. 8 and 9 40 the parts of the holder are similar to the parts in the embodiment shown in Figs. 1 to 5, inclusive, but the holder is not included in a hinge. The locking means is carried by a plate 20 which, when the door or window is moved to open position engages a plate 21 carried on the jamb.

In the embodiment shown in Figs. 10 to 12, 45 inclusive, the holder does not comprise a stop member of the type shown and described herein in other embodiments, but has a portion of the knuckle of the hinge carried by the leaf 3 serrated and the bolt 12^b of the locking means is arranged to engage the serrations when the door or window upon which 50 the hinge is used is opened or closed and to thereby hold the door in predetermined open position. This embodiment also includes a means for adjusting the tension of the spring 13 which consists of disk 22 against which 55 the spring bears and a set screw 23 by which the distance of the disk 22 from the end of the casing of the locking means may be regulated.

Although the embodiments shown vary in 60 details of construction in each of them there

is a member carried by the door or window and a member carried by the jamb and these members are moved relative to each other about the axis of the door or window when the door or window is opened. Also, each 70 embodiment includes a means for maintaining the members in fixed relation when the door or window is in open position whereby the door or window will be maintained in such open position. Other embodiments of 75 my invention may be made in which the parts are changed in size or arrangement without deviating from the spirit of my invention as included in the claims below.

What I claim as new and desire to secure 80 by Letters Patent, is:—

1. A holder for doors or casement windows comprising a member carried by the door or window and a member carried by the jamb, 85 said members being normally apart and arranged whereby when said door or window is opened said members will move into engagement with one another to limit the opening movement thereof, a spring actuated bolt carried by and arranged substantially parallel to one of said members, and removed therefrom so that the other of said members may be positioned between said bolt and said member by which said bolt is carried when said door or window is opened whereby said members will be maintained in fixed relation to maintain said door or window in opened 90 position.

2. A holder for doors or casement windows comprising a member carried by the 100 door or window and a member carried by the jamb, said members being normally apart and arranged so that when said door or window is opened said members will move about 105 axis of said door or window into engagement with one another whereby the opening movement of said door or window will be stopped, one of said members being adjustable relative to the other member whereby the extent of said opening movement may be varied, and automatic means actuated when said members are moved into engagement for 110 maintaining said members in such engagement whereby said door or window will be maintained in open position.

3. A holder for doors or casement windows included in a hinge and comprising a member carried by one leaf of said hinge and adapted to engage the free leaf of said hinge when said door or window is opened and thereby limit the opening movement thereof, means for adjusting said member whereby the extent of said opening movement may be varied, and automatic means actuated when said member moves into engagement with said free leaf for maintaining said member and said free leaf in engagement whereby said door or window will be maintained in open position.

4. A holder for doors or casement win- 130

dows included in a hinge and comprising a stop member arranged tangentially of the pin of said hinge and carried by one leaf of said hinge, said stop member being positioned and adapted to engage the free leaf of said hinge when said door or window is opened and thereby limit the opening movement thereof, means for adjusting said member relative to the leaf by which it is carried whereby the extent of said opening movement may be varied, and automatic means actuated when said stop member moves into engagement with said free leaf for maintaining said member and said free leaf in engagement whereby said door or window may be maintained in open position.

In witness whereof I have signed my name to the foregoing specification.

LESLIE W. BLOCK.
